CLARENCE A. SPRAGUE, OF EAST ORANGE, NEW JERSEY.

ACOUSTIC APPARATUS AND METHOD.

Application filed April 1, 1918. Serial No. 226,128.

This invention relates to acoustical instruments and methods.

An object of the invention is to provide a substitute for the diaphragm ordinarily employed in many acoustical instruments.

A further object of the invention is the provision of an improved form of diaphragm of general application.

A further object is the provision of an acoustical instrument which is free from certain defects ordinarily introduced by the vibratory elements of such instruments.

Other objects will be apparent from a reading of the following specification.

As is well known, every diaphragm has a natural period of its own by virtue of which its response to sounds of different frequencies is most vigorous at those frequencies near its own. This resonance effect produces distortion when a diaphragm is employed with voice controlled or sound reproducing instruments.

It has been proposed to overcome this defect by employing a diaphragm whose natural frequency is above the range of essential voice frequencies, or to provide damping means to keep the amplitude of vibration of the diaphragm small and uniform. The former expedient has the disadvantage that a diaphragm whose natural frequency is high enough to avoid resonance effects is very small and a small displacement of the central portion introduces high tension and brings the diaphragm to rest so that it will not transform sufficiently large amounts of energy. The second expedient mentioned has the disadvantage that it is impossible to provide damping means which will not dampen desired as well as undesired vibration, so that the device is inefficient.

A further disadvantage of a metallic diaphragm having a frequency within the audible range is that whenever it vibrates the character of the overtones is such as to introduce a metallic quality, which is often very noticeable in telephone reproduction. It is therefore desirable to have metallic diaphragms of such natural frequency as to render their vibration inaudible.

I propose to employ a small relatively freely moving piston in place of the diaphragm. I prefer to have this piston very light and as rigid as possible, so that it will easily follow the movement of the air or other gas in contact with it. When a wave passes from air to a tightly stretched or

heavy diaphragm much of the energy is reflected instead of being absorbed. This is obviated to a great extent by making the piston very light so that with a relatively small restoring force considerable displacements may be produced.

The piston is preferably held in its initial or neutral position by a small, light spring. The natural frequency of the vibrating system formed by the piston and spring is preferably above the range of essential frequencies impressed upon the piston. When speech is impressed, the natural frequency of the vibrating system may be 4000 or 5000 per second, or higher, the essential voice frequencies lying below this range. The natural frequency of the system may also be within the range of essential impressed frequencies, but a disadvantage above mentioned is then present.

The important feature is that the piston is light enough to follow the movement of the air with greater fidelity than a stretched or heavy diaphragm, and that it is free to vibrate with relatively great amplitude before being brought to rest by the suspending structure as in the case of a diaphragm.

With this arrangement there arises the disadvantage that the piston when used in a telephone transmitter is easily displaced bodily by the air currents set up by the voice of a speaker. To eliminate these air currents I propose to place a diaphragm across the mouthpiece at or near the large end of the same and to so construct this diaphragm that it has a frequency above the audible limit. The metallic character given to the reproduced speech is thus eliminated.

My reason for placing the auxiliary diaphragm at the large end of the mouthpiece instead of near the small end is that I am thus able to compensate for the smallness of the amount of energy which can be transmitted by a single diaphragm of exceedingly high frequency; for the greater area of cross section at the larger end of the mouthpiece permits the use of a plurality of such diaphragms in parallel, so to speak. That is, the total energy transmitted is the sum of that transmitted by the individual diaphragms, just as the amount of energy transmitted by a plurality of electric condensers connected in parallel in a line is the sum of that transmitted by the individual condensers. This energy is all concentrated upon the single small piston, which is able

to absorb and transmit much of it by virtue of its small mass and relatively great freedom of motion.

I prefer to use a light, rigid piston mount, 5 based upon slideable means, such as a pin having bearings as free from friction as possible, as described more in detail below. The piston can be made to transmit the energy of its motion to a microphone box or other movable element through the means upon which it is mounted or otherwise.

The improved diaphragm which I prefer to employ in connection with the piston is not limited to such use, but will find a wide 15 variety of uses in the acoustic arts, and the piston is not limited to use therewith.

My invention will be better understood by reference to the accompanying drawings in which:

20 Fig. 1 is an elevational view, partly in section, of a telephone transmitter according to my invention.

Fig. 2 is a fragmentary plan view, partly in section, of the arrangement shown in 25 Fig. 1.

Fig. 3 is an elevational side view, partly in section, of a form of my compound diaphragm.

30 Fig. 4 is an elevational front view of the diaphragm of Fig. 3.

Fig. 5 is a view in elevation of a modified form of piston.

35 Fig. 6 is a fragmentary view, partly in section, of the modification of Fig. 5 on an enlarged scale.

Fig. 7 is a view in elevation of a different modification of piston, also upon an enlarged scale.

40 In the drawings like reference characters refer to like parts throughout.

A conical shaped sound deflecting element 1, which is here shown as a mouthpiece of a telephone transmitter, is provided with a piston 4 of the kind described above. This piston is here shown as operating a microphone 2. The microphone box is held to the mouthpiece by means of straps 3. The pin 6 upon which the piston is mounted is attached to the front of an ordinary microphone box 45 such as that now generally employed in telephone transmitters. The front electrode 8 is suspended by the diaphragm 7 which may be of mica. This diaphragm is small and may well be much smaller than that ordinarily used. The front end of the pin 6 slides in a bearing in the support 5 whose base 13 is riveted or screwed to the mouthpiece 1. The granular carbon is shown at 10, the rear electrode at 9 and the lead wires at 11 and 12.

60 The compound diaphragm shown in Figs. 3 and 4 is designated by numeral 14 in Fig. 1 and is held in place by a ring 20, which may be fastened to the mouthpiece by screws 21.

65 The compound diaphragm consists of a membrane 16 of metal or other suitable ma-

terial plated or stretched over the face of a circular metal plate 15 of relatively very great thickness and mass. The membrane may be bent over the edge of the plate and held in place by the clamping ring 19. The membrane is preferably put under very high tension by any known means so that its natural period of vibration is very small. This may be done, for example, by stretching a sheet of the diaphragm material, placing the face of plate 15 thereagainst, placing ring 19 upon the opposite side of the diaphragm material co-axially with plate 15 and pressing the ring in place on the edge of the plate, all in a well-known manner. The plate 15 has a plurality of openings 16. A second plate 18 which is a duplicate of plate 15 except that it is preferably not so thick is clamped over the stretched membrane and held in place by screws or bolts 17 or by other clamping means. The membrane is thus made to function as a plurality of small diaphragms each of which has a natural frequency high as compared with that of the membrane as a whole. The natural frequency of each of the small diaphragms may easily be made to be above the upper limit of audibility.

In Figures 5 and 6 is shown a modified form of piston in which the pin 37 upon which the piston 31 is mounted is free to move in bearings 38 and 39 in the walls of the microphone box 30. A clearance space 40 is provided to reduce the friction in the bearings. The piston is held in place by spiral springs 33, 34 which may be tensioned by screw 36 which has its bearing in support 32. The forward spring may be attached to an arm 35 similar to arm 5 of Fig. 1. Springs 33 and 34 are shown by way of example. When a very high natural period is desired, a spring consisting of but a single turn or a portion of a turn of relatively very heavy wire is employed. The spring 34 may take the form of a pin, such as that shown in 43, Fig. 7. No novelty is claimed for the form of spring employed, as it is well known how to design springs so as to produce with a small mass a vibrating system having a high natural frequency of vibration.

In Fig. 7 is shown a form of mounting of 115 more general application. One side of the piston 50 is shown as unattached. The pin 41 has a bearing 42. A spring pin 43 is employed to position the piston. Adjustment may be made by means of the auxiliary 120 spring 44 and adjusting screw 45. This arrangement may be utilized, for example, with a microphonic box, such as 30, Figs. 5 and 6, by placing the left-hand face of the piston 40 in contact with the granular microphonic material. An oil cup 46 may be provided.

The term "acoustic" as used in this specification to describe a type of wave is intended to be taken in its broadest sense, i. e., with respect not only to sound waves of audible 130

frequency, but also similar material waves of frequency below or above the audible limit. It will be understood that many changes may be made in the embodiments of my invention shown and described without departing from the spirit of my invention as defined in the following claims. It is obvious that in the use of this invention, one or more of the features described above may be omitted and that certain advantages inherent in the invention will still remain. The invention is designed for use not only in the telephone art, but in other acoustic arts, including for example, the phonographic art and the production and reproduction of music. It will often be desirable to make use of the invention in one aspect only, many such aspects being defined in the following claims.

What I claim is:—

- 20 1. The method of utilizing vibratable sheet material in acoustic instruments for the setting up of desired waves of speech frequencies so as to eliminate acoustic wave distortion due to resonance effects, when the material is of a character and in a form to produce such distortion, which comprises restraining the sheet along lines forming boundaries to many very small, less restrained areas of high natural fundamental frequency as compared with the range of frequencies essential in speech reproduction, applying periodic force directly, simultaneously and in the same amount to said small areas, said force being within the speech range of frequencies, and preventing the sheet material from vibrating along any of said lines of restraint in a manner to introduce natural frequencies within the speech range.
- 40 2. The method of reducing acoustic wave distortion in vibratable sheet material of acoustic instruments when such material is of a character and in a form to introduce distortion due to the fundamental and harmonic-frequency resonance effects, which method comprises restraining the material along lines forming boundaries to many small, less restrained areas or segments so that the natural fundamental frequency of vibration of each of these segments is above the range of audibility and preventing the sheet material from vibrating along any of the lines of restraint in a manner which would introduce natural frequencies within the range of essential speech frequencies.
- 55 3. An acoustic vibrating diaphragm system comprising sheet vibratable material, a rigid framework having many small openings therein, means for holding said sheet material over said openings under tension to form diaphragms in said openings, each diaphragm having a fundamental natural frequency above the range of frequencies essential in the reproduction of speech, and means for applying driving force directly, and

simultaneously to each of said diaphragms.

4. An acoustic vibrating diaphragm system comprising sheet vibratable material, a rigid framework having many small openings therein, a second framework similar in contour to said first and having corresponding openings therein, means for holding said frameworks together with the openings in one registering with those in the other, with said sheet material therebetween and in firm contact with the peripheries of said openings to form diaphragms in the openings, the size of the openings, the character of the sheet material and the tension being chosen to give each diaphragm a fundamental natural frequency above the range of frequencies essential in the reproduction of speech, and means for applying driving force directly and simultaneously to each of said diaphragms.

5. In an acoustical instrument, the combination with the system of claim 3 of a wave deflecting wall enclosing a conical shaped space filled with gas having said system at the large end thereof, a vibratable piston of very small size and mass, means for suspending said piston in said opening concentrically therewith, a second vibratable element, and a rigid connecting means extending between said vibratable element and the face of said piston most remote from the face of said wall, the vibratable system comprising said vibratable element and said piston having a natural fundamental frequency of vibration above the range of essential voice frequencies.

6. The combination with an electric circuit of means for acoustically controlling the resistance of said circuit, comprising movable means of such sensitiveness that slight air currents interfere with its proper functioning, and means for protecting such movable means from air currents set up by the breath of a speaker, comprising a vibratable wall spaced from said, movable means and adapted to receive voice sound waves from a speaker and to transmit them toward said movable means, said vibratable wall having no natural period of vibration within the range of essential voice frequencies transmitted.

7. Means for producing waves within the range of speech and music frequencies comprising sheet vibratable material, means for restraining said material along lines forming boundaries to many small areas of high natural fundamental frequency as compared with the range of frequencies essential in speech reproduction so that the ear is substantially unresponsive to the resonant frequency of any of said areas, and means for applying periodic force directly, simultaneously and in the same amount to each of said small areas so that each will vibrate similarly and so that a plurality of said

small areas will not vibrate together as a unit having a natural fundamental frequency within the range of essential speech and music frequencies.

- 5. 8. Means for producing waves within the range of speech and music frequencies comprising sheet vibratable material, means for restraining said material along lines forming boundaries to many small areas of high natural fundamental frequency as compared with the range of frequencies essential in speech reproduction so that the ear is substantially unresponsive to the resonant fre-
- 10.

quency of any of said areas, means for applying periodic force directly, simultaneously and in the same amount to each of said small areas so that each will vibrate similarly and so that a plurality of said small areas will not vibrate together as a unit having a natural fundamental frequency within the range of essential speech and music frequencies, and a chamber into which said wave producing means works to set up sound waves therein.

CLARENCE A. SPRAGUE.
